UNITED STATES PATENT OFFICE.

JOSEPH ALPHONSE DEMERS, OF ST. ROMUALD, QUEBEC, CANADA.

AUTOMATIC TRAIN STOP AND SIGNALS

1,026,852.

Specification of Letters Patent.

Patented May 21, 1912.

Application filed May 9, 1910. Serial No. 560,388.

To all whom it may concern:

Be it known that I, JOSEPH ALPHONSE DEMERS, a subject of the King of Great Britain, residing at St. Romuald, county of 5 Levis, in the Province of Quebec, Canada, have invented certain new and useful Improvements in Automatic Train Stops and Signals; and I do hereby declare that the following is a full, clear, and exact description of the invention, such as will enable others skilled in the art to which it appertains to make and use the same.

The invention to be hereinafter described relates to railways, and particularly to automatic mechanisms for signaling, and applying the brakes, at predetermined points along the track.

In order to more clearly disclose the construction, operation and use of the invention, reference should be had to the accompanying drawings forming part of the present application.

Throughout the several figures of the drawings, like reference characters designate 25 the same parts.

In the drawings: Figure 1 is a vertical sectional view through the casing, showing the operating mechanism in elevation; Fig. 2 is a vertical cross section on line 2—2 of Fig. 1, looking in the direction of the arrow; Fig. 3 is an enlarged detail of the lever holding device; Fig. 4 is a side elevation of the device for operating the signal actuating lever; Fig. 5 is a side elevation of the 35 device for operating the brake actuating lever; Fig. 6 is a side elevation of a special trip mechanism for operating the actuating levers; Fig. 7 is a plan view of Fig. 6; and Fig. 8 is a side elevation of a modified form 40 of actuating device for the air brakes.

The main objects of the invention are to provide a simple and efficient mechanism for automatically sounding the signal, and setting the brakes, as the train is passing a predetermined point in the track, and to accomplish these operations entirely independently of the engineer or any other person.

The whole actuating mechanism is adapted to be mounted in a case or box 1, which may be conveniently suspended from the under frame of the tender. Within this case or box is pivotally mounted a lever 2, the short end of which projects from the bottom of the box and travels at a short distance above the track. To the upper end of

this lever is connected a cord or rope 3, which is passed over a pulley 4 and connected in any well known manner to a gong or other suitable signal in the cab of the engine. Consequently, whenever the lower end of the lever 2 is engaged by one of the trip devices 6, mounted adjacent the track, it will be swung to position to operate the signal. As soon as the signal has been sounded, the brakes should be applied. To effect this, a second lever 15 is pivotally mounted in the case or box 1. The upper end of this lever is connected by a link 16 to the handle of the valve, controlling passage 70 of air through the pipes 17 of the air brakes. To the lower end of the lever is pivotally connected a sliding bar or rod 18 adapted to be engaged and operated by a trip device 19 pivotally mounted adjacent the track. 75 This trip device is held in upright position by means of springs 21, which are connected at their opposite ends respectively to an eye 22 extending from the trip 19 below its pivotal point, and to the upturned ends of a 80 plate 23 in which the trip is mounted. This yielding connection holds the trip 19 normally in operative position, while at the same time permitting it to be forced down by the bar 18 as the train advances. However, before the tension of the springs 21 is overcome, the bar 18 will be driven rearwardly in the casing sufficiently far to cause 85 swinging of the lever 15 and consequent operation of the air brake valve. The trip 19, 90 of course, is returned to operative position by the springs 21.

In order to have the actuating levers 2 and 15 operate successively, the trips 6 and 19 are placed at a considerable distance 95 apart, and so arranged that the trip 6 will engage the lever 2 before the trip 19 engages the rod 18.

A somewhat simpler form of mechanism for operating the valve of the air brake pipe is shown in Fig. 8. By the construction shown in Fig. 8, a single rod 25 is substituted for the lever 15, link 16, and rod 18. This rod 25 is slidably mounted in straps 26 secured to the inner wall of the case, 105 and has a sliding pivotal connection with the handle of the air brake valve. A collar 27 is formed on the rod 25, and a spring 28 is coiled about the rod and arranged between the upper strap and collar, acting to 110 keep the rod normally in its lowered position. The lower end of the rod is provided with

a roller 29 adapted to engage an inclined plate 30 mounted adjacent the track. As the roller is forced up the incline, it will raise the rod 25 and operate the air brake valve. The lower end of the rod is provided with a hinge joint 31 and a cord 32 is connected to the lowest part and passed over suitable pulleys and into the engineer's cab within easy reach. By pulling on this cord, he can swing the lower end of the rod 25 upward to inoperative position and out of the path of the inclined plate 30. The back of the hinge joint is braced by a block 33, to prevent its giving, when the roller 29

10 meets the incline 30. The rod 25 is provided with a pin 34, adapted to engage a leaf spring 35. As the rod 25 is forced upward, the pin 34 will be forced over the bend in the spring 35 and the spring will

20 hold the rod raised and keep the brakes set.

In order to raise the bar 18 to inoperative position, a rope 32', corresponding to the rope 32 of Fig. 8, is used. This is connected to the bar, passed up over pulleys 36, and into the engineer's cab near his seat. If he desires to raise the bar to inoperative position, he simply pulls the rope 32'. The bar 18 may be held in raised position by the spring 35 in the same manner as the rod 25 is held in raised position. A pin or rod 100' carried by the lever 2 and adapted to engage the back of the lever 15 acts to limit the forward position of the bar 18.

35 Emergency trip devices may be placed at points near stations, if desired, so that they may be set to automatically stop a train or to warn the engineer, in case of a mix-up in despatches, or for other reasons. The 40 emergency trips correspond to the trip 19. However, in order to keep the trip normally inoperative, it is inclosed with a box having a lid 40. This lid is swung down over the trip 19 and secured in place by a bolt 41 which 45 engages a hook 42 secured to the under side of the cover. This bolt is formed as a lever and fulcrumed in the casing at one side of the top 40. To the free end of the bolt is secured one end of the operating wire or

cord 43, which is passed over suitable rollers 50 and secured to a winding drum 44 operated by pawl and ratchet mechanism. Of course, as soon as the bolt is disengaged from the hook, the springs will drive the trip 19 and cover 40 upward, so that the trip will 55 be in operative position. Bolt 41 is held in operative position by means of a spring 90 having its opposite ends secured, respectively, to a lug on the under side of the cover plate, and to the bolt.

60 It is thought that the operation and use of the invention will be clear from the preceding detailed description.

Changes may be made in the construction, arrangement and disposition of the several 65 parts of the invention, without in any way departing from the field and scope of the same, and it is meant to include all such within this application, wherein only preferred forms have been disclosed.

70 Having thus fully described my invention, what I claim as new and desire to secure by Letters Patent, is:—

1. A device of the character described, comprising an air brake pipe, a controlling 75 valve therefor, a casing, a bar slidably mounted in said casing, a lever pivoted in said casing and connected to one end of said bar, connections between said levers and said controlling valve, means for holding 80 said bar in inoperative position, and a trip adapted to operate said bar.

2. A device of the character described, comprising an air brake pipe, a controlling 85 valve therein, a casing, a bar slidably mounted in said casing, a lever pivoted in said casing and connected to one end of said bar, connections between said lever and said controlling valve, means for moving said bar to inoperative position, and a trip adapted to 90 operate said bar.

It witness whereof I have hereunto set my hand in the presence of two witnesses.

JOSEPH ALPHONSE DEMERS.
